WILLIAM KERR, OF PHILADELPHIA, PENNSYLVANIA, ASSIGNOR TO JAMES BROMLEY & BROTHERS, OF SAME PLACE.

Design No. 4,315, dated August 30, 1870.

DESIGN FOR A CARPET PATTERN.

The Schedule referred to in these Letters Patent and making part of the same

I, WILLIAM KERR, of Philadelphia, county of Philadelphia, State of Pennsylvania, have invented produced a Design for a Carpet-Pattern, of which the following is a specification.
The accompanying drawings represent sufficient of carpet to illustrate my design, which consists of a series of leaves, A, each leaf being contained in a circle formed by foliated branches, a, as shown.
Irrespective of the colors employed,
[claim—

The design for a carpet pattern, substantially as described and illustrated in and by the accompanying drawings.

In testimony whereof I have signed my name to this specification in the presence of two subscribing witnesses.

WILLIAM KERR.
